United States Patent Office

Des. 187,062
Patented Jan. 12, 1960

187,062

COMPOSITION FLOOR COVERING OR THE LIKE

Beatrice Edesess, Brookline, Mass., assignor to American Bilrite Rubber Co., Inc., Chelsea, Mass., a corporation of Delaware

Application September 12, 1958, Serial No. 52,618

Term of patent 14 years

(Cl. D92—4)

Fig. 1

Fig. 2

Fig. 1 is a plan view of a composition floor covering showing my new design. The arrows on the figure indicate a design unit which is repeated in regular succession.

Fig. 2 is a view on an enlarged scale showing a portion of the design.

I claim:

The ornamental design for a composition floor covering or the like, substantially as shown and described.
